FIRE-PROOF BUILDING CONSTRUCTION UNIT

Ilia E. Hobart, Mount Vernon, N. Y.

Application July 2, 1951, Serial No. 234,761

2 Claims. (Cl. 189—34)

The present invention relates to certain new and useful improvements in hollow sheet metal fire-proof building and construction units such as, for example, partitions, doors and the like, and has more particular reference to stabilizing and warp-proofing spacer ribs which are interposed between the main plates or panels of said unit.

The principal object of the invention is to unite the stated panels or plates by spacing and reinforcing ribs, the latter being interposed between the interior surfaces of the plates and means being provided on the plates whereby the longitudinal edge portions of the ribs may be satisfactorily keyed to said plates, whereby the plates are maintained in precise spaced parallelism and bulging and sagging of said plates is reduced to a minimum.

Another object of the invention is to utilize ribs of asbestos-board or equivalent material of equal insulating properties, whereby to retard heat transference from one plate to the other plate.

Another object of the invention is to provide a simple, practical and economical hollow fire-proof building construction unit in which manufacturers and users will find their respective requirements and needs fully met and contained and in which the municipal requirements of ordinance departments, in respect to fire resistive constructions, will be aptly met.

Briefly summarized, the invention has to do with a unit embodying a pair of flat metal spaced parallel plates, an asbestos keying and warp-proofing rib interposed between said plates, means on the interior of one plate providing a separable snap-joint connection between said plate and rib, corresponding means on the interior of the remaining plate providing a separable snap-joint connection between said latter plate and mating portion of said rib, whereby to allow said plates to be joined to and united with said rib in directions at right angles to the longitudinal axis of said rib.

Then, too, novelty is predicated on the foregoing simplified assemblage of plates and one or more ribs, in conjunction with channel-shaped stiles having interlocked connection with the longitudinal edges of said plates and closing the corresponding spaces between the plates, and telescoping channel-shaped top and bottom capping members closing in the corresponding spaces of said plates and end portions of said stiles and having permanent welded joint connection with said plates and stiles. Other objects and advantages will become more readily apparent from the following description and the accompanying sheet of illustrative drawings.

In the accompanying sheet of drawings, wherein like numerals are employed to designate like parts throughout the views:

Figure 1 is a perspective view of a fire-proof building construction unit (specifically a flush door) with stiles constructed in accordance with the principles of the present invention.

Figure 2 is an enlarged fragmentary section taken approximately on the vertical line 2—2 of Figure 1, looking in the direction of the arrows.

2

Figure 3 is an enlarged, but contracted, elevational and sectional view on the horizontal line 3—3 of Figure 1, looking in the direction of the arrows.

Figure 4 is an enlarged fragmentary top plan and sectional view, like Figure 3, of a pan-type flush door without stiles, detailing the construction of one of the fire resistive ribs and means keying same to the complementary seam-welded pans.

Novelty is primarily predicated, as will be evident, on 10 the composite reinforcing and heat resistive rib construction shown in detail in Figure 4 and shown fully installed in Figure 2. Additional novelty is predicated on a door made up as shown in Figure 1, no novelty being claimed for the specific interlocking devices or means between 15 the stiles 22 and sheet plates 6 and 8 depicted in Figure 3. It is obvious that the unit in Figure 1 may represent a door, partition, or the like, and the description is to be interpreted accordingly.

The flat rectangular spaced parallel metal or equivalent 20 sheet material plates are denoted by the numerals 6 and 8, these being duplicates of each other. The numeral 10 (Figures 3 and 4) designates a suitable insert or filler of asbestos or other fire-proof material which may, if desired, be employed as a supplemental spacer and sound 25 deadening element. Any number of the improved fire resistive, reinforcing or stabilizing ribs may be provided. A description of one will suffice for all. To this end, the rib is preferably of hard asbestos-board and is denoted by the numeral 12 in Figures 3 and 4 and is generally rectangular in cross-section. The opposite longitudinal edge portions of each rib are fashioned into truncated or wedge-shaped keying heads 14—14. The longitudinal sides or faces 15—15 adjacent the heads 14—14 are provided with keeper grooves 16—16. The grooved 30 and headed edge portions of the rib 12 are fastened respectively to the interior surfaces of the plates 6 and 8 by way of metal or equivalent adapter and keying channels 17. These are of suitable metal and have thin bight portions welded in place, as shown. Each channel 17 has longitudinal converging flanges 18—18 and these have 35 their edge or lip portions terminating in V-shaped assembling and retaining tongues 20. The flanges are resilient and the tongues are adapted to "snap" into the keeper seats provided by the stated keying grooves 16. The rib 12 may be slid lengthwise into the channel or keyway provided by said channel 17; or, the headed edge 14 of one side of the rib 12 may be snapped into the co-acting 40 adapter channels on one plate 6 and then the other plate 8 forcibly snapped over the remaining head 14 on the opposite side of the rib. This snap-jointure connection 45 between opposed adapter channels 17 and rib 12 is highly important in that the connection may be made in directions at right angles to the longitudinal axis of the rib, as is obvious. It is also within the purview of the invention (not shown) to have the keeper grooves formed 50 in the flanges 18 and tongues formed along the opposite faces of the rib, whereby to provide an alternate snap-joint connection between the parts. The left and right stiles 22—22, are channel-shaped in cross-section and are 55 of metal and abut the longitudinal offset edge portions of the plates 6 and 8, in the manner shown best in Figure 3. Here the walls of the stile 22 are provided with return bends 24 providing keepers for the laterally offset edge portions 26—26 of the plates 6 and 8. An interlocking 60 insert of channel-shaped form is also provided as at 28. It is understood, however, that the invention merely has to do with stiles 22—22 closing in the spaces between the longitudinal edges of the plates 6 and 8 and suitably interlocked as specifically shown or otherwise connected 65 with said plates. The upper and lower telescoping channel caps 30 and 32, also sometimes called end-pans, are fitted inside between the open ends of the stiles 22—22.

70

and upper and lower open ends of the plates 6 and 8 and are welded or otherwise secured in place to close in all spaces. Suitable vent holes are provided as at 34. In practice, with respect to the flush door with stiles 22-22 the channel caps or pans 30 and 32 are swaged, as shown at 36, to fit around and accommodate the means 24 and spot welded to both plates 6 and 8 and the stated stiles 22-22.

A building unit characterized by the facilities and improvements herein disclosed will promote, obviously, a saving of time, labor and material. The components may be expeditiously assembled to produce the desired end product; namely, a better fire-proof, hollow construction unit unique in that it embodies the improved rib means with the ribs 12 preferably of asbestos or equivalent heat-retarding properties.

It is to be understood that the invention has to do with a flush-type door with stiles (Figures 1 to 3) as well as a flush pan-type door (Figure 4) which is without the shown and described stiles 22-22. This type is shown in Figure 4 and the "plates" here take the form of pans 6a and 8a having lateral flanges 7-7 which are butted and are welded or seam welded as shown. By "invention" here is meant the aforementioned rib 12 and keying adapters or channels 17-17.

Minor changes in shape, size, materials, and arrangement of parts may be resorted to in actual practice without departing from the spirit and scope of the invention as claimed.

Having described the invention, what is claimed as new is:

1. A fire-proof building construction unit embodying a pair of flat metal complementary plates, a first complementary adapter channel affixed to the interior surface of one of said plates, said adapter channel being of a length commensurate with the length of said plate and embodying a web portion superimposed upon and directly joined with the plate and including lengthwise flanges converging toward each other and having free terminal edge portions provided with V-shaped assembling and retaining tongues, a second adapter channel complementary to said first adapter channel and identical in construction also

5 having a web portion superimposed upon and directly secured to the interior surface of the other plate and including converging lengthwise flanges having free edge portions terminating in V-shaped assembling and retaining tongues, a rigid keying and warp-proofing rib solid in cross-section and constructed of insulation material and located between the plates and of a length corresponding with the length of each adapter channel, the longitudinal edge portions of said rib telescoping between the respective flanges of the respective adapter channels and the longitudinal edges of the rib being in direct contact with the coating web portions, the opposite side surfaces of said rib having lengthwise grooves and said tongues being snapped into and held in their respective cooperating grooves, whereby the rib thus serves to separably interconnect the plates in spaced parallelism.

2. The structure defined in claim 1 wherein the lengthwise edge portions of said rib are wedge-shaped in cross section and are thus adapted to spread the V-shaped tongues and cooperating flanges apart during the act of seating said edge portions in the channels and permitting the plates to be thus keyed together by way of the rib and adapter channels in directions at right angles to the lengthwise axis of said rib, and the combination therewith of 20 readily applicable and removable means cooperating with the respective longitudinal and transverse edge portions of the spaced plates and substantially closing the transverse and longitudinal portions of the spaces which would otherwise exist between said plates.
